SCREW OFF PACKER

Leslie A. Layne, Albert L. Roco, and Harold C. Block, Houston, Tex.; said Roco and Block assignors to said Layne

Application May 6, 1935, Serial No. 19,960

20 Claims. (Cl. 166—10)

The invention relates to a screw off packer for wells wherein a seal is to be obtained either between a larger string of pipe or the surface of the well bore itself.

5 It is one of the objects of the invention to provide a packer assembly which is adapted to support a string of pipe in which the packer may be incorporated.

Another object of the invention is to provide 10 a packer assembly which is particularly adapted for very deep wells wherein a part of the weight of the string of pipe above the packer may be used to set the packer and the assembly will thereafter support the balance of the weight of 15 the string of pipe so that there will be no tendency to destroy the packer by the application of excessive weight.

Another object is to provide a packer which 20 will be securely sealed against leakage from inside of the string of pipe in which the packer is incorporated.

Another object of the invention is to provide 25 a seal off packer in which the weight of the string of pipe above the packer serves to maintain the packer in expanded position and to also maintain a seal against leakage under the packer.

Another object of the invention is to provide 30 a two-part packer of the screw off type wherein part of the packer rotates during the unscrewing operation and the remainder of the packer remains stationary.

Another object of the invention is to provide 35 a screw off packer wherein the packing is not subjected to distortion during the unscrewing operation.

Another object of the invention is to provide 40 a stop portion for a screw off packer so that the load of the pipe above the packer will not be supported on the packer.

Still another object of the invention is to provide 45 a screw off packer having a setting sleeve which will telescope under a portion of the packer after it has been partially set to obtain additional expansion of that part of the packer.

A still further object of the invention is to provide 50 a setting sleeve which telescopes beneath the packer fabric so that any leakage under the packer will be compelled to travel twice the length of the setting sleeve.

Other and further objects of the invention will 55 be readily apparent when the following description is considered in connection with the accompanying drawing wherein:

Fig. 1 is a central vertical sectional view of the 55 packer incorporated in a string of pipe in position to be lowered into the well.

Fig. 2 is a central vertical view showing the 60 packer in expanded or sealing position.

The drawing illustrates a string of pipe 2, which 60 may be of any desired size or length, which is

being lowered into a well bore. This string of pipe will be made up of pipe sections connected together by couplings 3, and may extend above and below the packer which is illustrated generally at 4. The lower section of pipe 5 serves as a support for the packer and the lower end of this pipe may have a screen, liner, or casing on the lower end thereof so long as this pipe 5 is rigidly supported to form a foundation for the packer.

The pipe 5 has connected thereto the stop collar 6, which has the support pipe 7 threaded thereto. The top of the collar 6 provides a shoulder 8 on which the wrappings of material forming the packing 9 are arranged. Suitable wires 10 will be wound about the packing at 11 to retain the lower end thereof in fixed position. This packing 9 is arranged by winding it about the pipe 7 to form what will be termed the bottom or lower packing member 13. The upper end of this packing material is also confined by wires 11. This packing member 13 may be of any desired length in order to obtain the necessary expansion when it is collapsed longitudinally.

The support pipe 7 continues above the lower 25 packing member 13 and has fixed thereto the bushing 16 whose outer surface carries a coarse thread 17. The upper end of this bushing 16 provides a seat 18 for a ring of sealing material 19, which is surmounted by a compression ring 20. 30 A stop ring 21 is threaded on the pipe 7 in order to retain the sealing material and compression ring in position. A setting sleeve 25 has its inner surface provided with a coarse thread 26 which cooperates with the coarse thread 17 to provide 35 the screw off connection for the packer. The setting sleeve 25 is undercut to form a shoulder 27, which serves as an abutment for the upper end 28 of the top packing portion 30 of the packer. This upper portion will be confined by wires 11, 40 the same as the previous packing material.

The setting sleeve 25 continues below the shoulder 27 but is of a reduced thickness as at 32 and gradually tapers off at 33 to the lower end 34, which is, as illustrated, very thin. The bottom 45 of the top packing portion 30 of the packer is also confined by wires 11 directly adjacent the lower end 34 of the setting sleeve. It will be noted that a space 38 is provided between the lower end 39 of the top packing portion 30 and 50 the upper end 40 of the bottom packing element 13. This space 38 will be of substantially the same length as the threaded screw off connection between the threads 17 and 26.

The upper end of the setting sleeve 25 is 55 threaded to the swaged nipple 42 which has an inwardly directed shoulder 43 which is positioned some distance above the upper end 44 of the support pipe 7.

With the parts assembled in the position shown 60

in Fig. 1, the device will be lowered into the hole where the packer is to be set and is preferably incorporated in the string of pipe 2 as a part thereof. It is to be understood however that this 5 packer may be made up as a separate assembly which is merely attached to any desired strainer, liner, or casing, which is illustrated by the pipe 5.

When the packer is to be set it is only necessary to rotate the string of pipe 2 in a right-10 hand direction so that the threads 26 rotate upon the threads 17 and the setting sleeve moves downwardly relative to the support pipe 7. This support pipe 7 is, of course, held stationary by the engagement of the pipe 5 on the bottom of 15 the hole.

As the setting sleeve 25 rotates, the upper packing portion 30 will, of course, rotate therewith. It will be noted that the sleeve 25 is undercut at 45 so that there will be no excessive 20 frictional resistance to rotation. During this rotation of the setting sleeve the lower packing portion 13 will remain stationary because it is fixed on the support pipe 7. As the setting sleeve and packing portion 30 move downwardly 25 the lower end 39 of the upper packing portion will come into engagement with the upper end 40 of the lower packing member 13. When this occurs, the expansion of both packings will begin. At approximately the same time the 30 threads 26 will be entirely screwed off of the threads 7 so that the setting sleeve will be released from the bushing 16 and the upper section of the string of pipe 2 will be free to move downwardly in order to expand the packings 13 35 and 30. As the setting sleeve moves downwardly the two packings are confined between the shoulder 8 on the stop collar 6 and the shoulder 27 on the setting sleeve until they are expanded into the position shown in Fig. 2. The 40 lower packing member 13 begins its expansion as the thin edge 34 of the setting sleeve begins to telescope thereunder. In this manner the packing member 13 begins its expansion and thereafter is wedged further outwardly because of the 45 increasing thickness of the setting sleeve 25 as it telescopes beneath the upper end thereof. Because of this arrangement a double expansion of the packer is obtained and a perfect seal is thereby insured. The upper packing portion 30, 50 of course, telescopes upwardly on the setting sleeve, as shown in Fig. 2, so that it is also expanded outwardly because of the increasing thickness of the setting sleeve.

The wedging action of the tapered sleeve serves 55 not only to expand the packings from the inside while they are being collapsed longitudinally, but also serves to wedge the inside of the packing material firmly in position so that there can be no leakage underneath the packing. Before any 60 fluid may leak under the packing it is necessary that it traverse at least twice the length of the setting sleeve 25 because it must flow downwardly inside of the sleeve and then upwardly outside of the sleeve or vice versa. It seems 65 obvious that the abutment of the ends 39 and 40 together will prevent any leakage between the upper and lower packings.

The packing or seal ring 19 is of particular advantage because when the parts are assembled as 70 shown in Fig. 2, considerable pressure may be applied to the inside of the string of pipe 2 in order to wash down any cavings in the well or to maintain a circulation while the string of pipe 2 is being run into the well. This seal 19 prevents any leakage through the screw off joint 75

and is of advantage because of the coarse nature of the threads 17 and 26, which are not adapted to maintain a seal.

With the very long strings of pipe which are now being set in the wells the entire weight of the string of pipe can not be advantageously lowered onto the packer and maintained thereby without danger of cutting or shearing off the packer completely. With the present arrangement a construction has been provided whereby 10 if the packer is completely set no more weight can be applied thereto. This advantage is effected because of the shoulder 43 which is adapted to first engage the outer corner 58 of the compression ring 20 as it moves downwardly to 15 complete the expansion of the packer. The shoulder 43 as it engages the compression ring 20 causes this ring to move downwardly a short distance to effect compression of the seal 19 and insure that a tight joint will be maintained at 20 this location.

As soon as the compression ring moves downwardly a short distance the shoulder 43 comes into engagement with the corner 51 of the locking ring 21 on the top of the pipe 7, which is 25 of sufficient strength to support the weight of the string of pipe in the well. A positive stop is thereby provided for the weight of the pipe after the packer has been collapsed and this weight can not be applied to the packer but is transferred downwardly to the support pipe 7 and there is, of course, no tendency to shear off or cut off the packer.

It seems obvious that a seal is obtained inside of the packer so that there can be no leakage of fluid in either direction. The seal 19 is assisted in the sealing operation of course because of the length of the setting sleeve 25 and the fact that it has been wedged underneath the packing material of both the upper and lower packings.

The threads 17 and 26 prevent collapse of the packer while it is being lowered into the well bore and the fact that the upper and lower packings are positioned on the setting sleeve and the support pipe respectively prevent any twisting or distortion of the layers of fabric making up the packing while the screwing off operation is being carried on.

While one form of the invention has been 50 shown and described it seems obvious that the length and size of the packings and sleeves may be varied as desired.

What is claimed is:

1. A packer including a support pipe, a stop 55 collar thereon, a setting sleeve telescoped over said pipe, said sleeve being tapered downwardly to a thin edge, a threaded connection between said pipe and sleeve, a seal adjacent said connection to prevent leakage under said sleeve, and a 60 packer disposed on said pipe above said collar and on said sleeve whereby said sleeve will telescope under said packer during the sealing operation.

2. A well packer comprising a setting sleeve, 65 a packing member thereon, a support pipe telescopically related to said setting pipe, a packing member thereon, a setting pipe connected to said sleeve, a releasable connection between said support pipe and said setting sleeve so that said 70 sleeve may move on said pipe to abut said packings, and a tapered end on said sleeve to telescope under the contact faces of the packings upon setting.

3. A well packer comprising a setting sleeve, 75

- a packing member thereon, a support pipe telescopically related to said setting pipe, a packing member thereon, a setting pipe connected to said sleeve, a releasable connection between said support pipe and said setting sleeve so that said sleeve may move on said pipe to abut said packers, and means on said sleeve to telescope under said support pipe packer.
4. A packer including a support portion, a setting portion telescopically related to said support portion, and a wrapped fabric packing on each of said portions to abut together to be collapsed upon relative movement of said portions.
5. A string of pipe to be set in a well, a packer incorporated in said string, a pair of relatively movable pieces of pipe in said string, a screw off connection between said pieces, a fabric packing of layers on each piece of pipe to abut against each other when said pieces are telescoped after said connection is screwed off.
6. A packer to be incorporated in a long string of pipe comprising, a support portion, a setting portion telescopically related to said support portion, a separate packing on each portion, both of which are to be collapsed by movement of said portions, a releasable connection between said portions, and co-engageable shoulders carried by said portions to carry the weight of the string of pipe after the packer has been set.
7. In a packer, a support pipe, a setting pipe telescopically related to said support pipe, a sealing material to be compressed upon setting of the packer to form a seal between said pipes, and interengaging means on said pipes to support the weight of the setting pipe independently of said seal.
8. The combination in a screw off packer structure of a two-part packing to seal the outside of said structure, a screw-off connection, and a sealing material to seal against leakage through said structure.
9. A telescoping packer comprising a support pipe, a setting pipe, a packing portion on each of said pipes, and an additional packing arranged between said pipes, and a screw-off connection between said pipes so that on telescoping of the pipes all three packings will be compressed.
10. A packer to be incorporated in a long string of pipe comprising, a support portion, a setting portion telescopically related to said support portion, a threaded screw-off connection for said portions, a packing to be collapsed by movement of said portions, co-engaging shoulders carried by said portions to carry the weight of the string of pipe after the packing has been set, and a seal between said portions to be set upon engagement of said shoulders.
11. A packer including a support portion, a setting portion telescopically related to said support portion, said portions being relatively rotatable, and a packing on each of said portions to abut together to be collapsed upon relative longitudinal movement of said portions, but which are capable of relative rotation of said portions before setting without distorting either of said packings, and a screw-off connection between said portions releasable to effect setting of said packings.
12. A packer including a two part packing, a support pipe, a setting pipe telescopically related to said support pipe, one part of said packing being fixed to each pipe, a tapered end fixed on said setting pipe underlying one of said packings and adapted to have the other of said packings telescoped thereon during the setting operation.
13. A packer including a two part packing, a support pipe, a setting pipe telescopically related to said support pipe, a releasable connection between said pipes, one of said parts of packing being on each of said pipes and spaced apart whereby the pipes and packing parts are relatively rotatable without affecting said packing during the releasing of said connection.
14. A packer comprising a setting pipe, a support pipe telescopically related with and releasably connected to said setting pipe, said pipes being relatively rotatable to release said setting pipe from said support pipe for longitudinal movement, a two part packing one part being positioned on each of said pipes and spaced from the other part whereby said packing parts are unaffected by the rotation of said setting pipe.
15. The combination of a setting pipe with a packing thereon, a support pipe telescopically related to said setting pipe and with a packing thereon, a screw-off connection between said pipes normally spacing said packing apart but releasable to allow relative longitudinal movement of said pipes to abut said packing for expansion thereof.
16. A packer construction wherein the parts are relatively rotatable to set the packing without causing twisting of the packing during rotation comprising a support pipe, a setting pipe, a screw-off connection between said pipes, a packing portion on each pipe which portions are spaced apart during rotation and adapted to be expanded upon longitudinal movement of said pipes.
17. A packer including a support pipe, a setting sleeve telescoped over said pipe, means to connect said sleeve and pipe, a packer between said sleeve and pipe, a seal member inside of said sleeve to normally form a seal between the sleeve and pipe before the packer is collapsed, said means being releasable to collapse said packer, and interengageable parts on said sleeve and pipe to cause said seal member to form a seal when the packer is set.
18. A packer including a support pipe, a setting sleeve telescoped over said pipe, means to connect said sleeve and pipe, a packer between said sleeve and pipe, a seal member inside of said sleeve to normally form a seal between the sleeve and pipe before the packer is collapsed, said means being releasable to collapse said packer, interengageable parts on said sleeve and pipe to support the weight of the pipe when the packer is set.
19. In a telescoping packer a support pipe for the packing, a gland thereon, a seal ring on said gland, a compression plate above said seal, and means to hold said plate and seal ring against said gland.
20. In a packer a support pipe for the packing, a gland thereon, a seal ring on said gland, a compression plate above said seal, means to hold said plate and seal ring against said gland, a setting member telescopically related to said support pipe, and a releasable connection between said gland and said member to allow setting of said packer.
